(57) **CLAIM**

The ornamental design for an energy storage charger, as shown and described.

DESCRIPTION

1. Energy storage charger

1.1 : Perspective

1.2 : Front

1.3 : Back

1.4 : Left

1.5 : Right

1.6 : Top

1.7 : Bottom

Title of the design: charger with energy storage; The charger with energy storage is used for storing energy and charging; Design 1 claim the overall shape of the design; The most representative drawing or photograph is the perspective view.
